United States Patent Office.

PETER C. RENIERS, OF PITTSBURG, PENNSYLVANIA.

Letters Patent No. 94,977, dated September 21, 1869.

IMPROVED BASKET FOR GRINDING TILE.

The Schedule referred to in these Letters Patent and making part of the same.

To all whom it may concern:

Be it known that I, PETER C. RENIERS, of Pittsburgh, in the county of Allegheny, and State of Pennsylvania, have invented a new and useful Improvement in Basket for Grinding Tile; and I do hereby declare the following to be a full, clear, and exact description thereof, reference being had to the accompanying drawing, making a part of this specification, in which—

Figure 1 is a plan view of my improvement; Figure 2 is a side view thereof;

Figure 3 is a sectional view of one of the sides of the basket, as made by a plane passing through it in line $x-x$, fig. 2;

Figure 4 is a like view of the same, as made by a plane in the line $x'-x'$, fig. 2; and

Figure 5 is a like view of the central or main part of the basket, as made by a plane passing through it in the line $y-y$, fig. 2.

Like letters of reference indicate like parts in each.

The nature of my invention consists in the construction of a basket for grinding the edges of marble or other stone, tile, slabs, or plates, whereby any desirable number of them may be ground at once, and to any desired shape, by properly adjusting them in the basket and holding them on the revolving rubbing bed.

By the mode heretofore in use, such slabs or tile are ground one at a time, by being held by the workmen in the proper position on the rubbing-bed, which is revolved by steam, or other power, and the edges are thus ground down by frictional contact. This process is slow, and sometimes difficult, especially in grinding tile to a pentagonal or other than a square form, on account of the difficulty of holding the slab or tile perfectly true on the rubbing-bed.

By my improvement, I adjust to any desired angle, or one to one angle and another to another, a number of slabs or tiles in a basket, so that when set on the rubbing-bed the edges to be ground will rest on the bed, when, by causing the bed to revolve, the slabs or tiles will be ground on such edges to the desired angle.

To enable others skilled in the art to make and use my invention, I will proceed to describe its construction and manner of use.

a is a frame, strongly made of cast-iron or other suitable material, corresponding somewhat in construction to a flask for moulds, as used in casting. It may be of any desired size, or made to receive any desired number of tiles. As is shown in the drawing, it is made to hold four tiles inside, and two are to be fastened on outside.

It is divided transversely by a diaphragm, a' .

In each end I then place a removable partition, b , running lengthwise of the frame.

Each partition b is set in grooves in the end pieces of the frame a , so as to be held against moving sideways.

Through each partition b , or in each side thereof, at or about its centre, I insert a threaded screw, c , supporting it, if need be, against being driven out of place by a jam-nut, c' .

Between the outer end of each screw and the side of the frame a , contiguous thereto, is left space enough for a pressing-block, d , and for the insertion between the block d and frame a , of the slab or tile f to be ground.

Pressure is applied to the slab or tile f , so as to hold it securely in any desired position, by a threaded nut, e , operating against the pressure-block d , or against a spring, e' , of elliptic or other suitable form, the ends of which spring bear against the pressure-block d .

The spring e' is punched at the middle, so as to pass over the screws c , and its ends are slotted, as at s , so as to admit guiding-pins s' .

The partitions b and pressure-blocks d may rest on a ledge, g , in the bottom of the frame a , or be supported therein in other suitable manner.

The devices thus far described are designed chiefly for grinding the edges of square or rectangular slabs.

For the purpose of grinding off the corners, and making tile of other polygonal shape than square or rectangular, I attach, by headed screw-bolts n , to the outside of the frame a , inclined rests m .

By the same screw-bolts n , and holding them in place by nuts n' , I attach the bars m' .

The slabs or tiles, the corners of which are to be ground, are inserted in the spaces between the bars m' and the sides of the frame a , with their edges on the inclined rests m . Their corners will then project down below the frame a , so as to come in contact with the rubbing-bed below, and by it be ground to the angle required.

The rests m are made thin, so that by turning up the nuts n' the bars m' may be pressed tightly against the tiles, and hold them securely in place.

In order that the rests m may be adjustable, I make slots o in the frame a , through which the bolts n pass; also like slots o' in the ends of the bars m' , the slots in each case extending lengthwise of the part in which they are made, as shown. It will then be observed that the inclined rests m can be adjusted further apart or nearer together, so as to be adapted to receiving different sizes of tile or slab, and holding them so that their corners may be ground off to the desired angle.

The inclined rests may also be slotted where the bolts pass through, if so desired, so as to be adjusted at different angles with reference to each other.

The basket, constructed as described, being filled with slabs or tile f , one or more between each pressure-

block *d* and the frame *a*, and also inside of each set of bars *m*, the basket is set on the revolving rubber-bed usually employed in grinding such articles, or may be applied to other devices constructed for a like purpose.

At the corners of the frame *a* are attached removable feet *l*, made of any suitable material.

The tile may either project below the lower ends of the feet *l*, or be even with them; in which latter case the feet *l* will be ground off along with the projecting edges of the tile.

When the feet are ground down they can be easily and cheaply renewed.

The basket, with the tile, is held on the rubbing-bed as it revolves, and if desired, it may be shifted in position thereon from time to time, so that all the tile shall be brought into contact with the wet grit or pulverized particles ground off, and all the edges be ground uniformly.

When the grinding is finished the tile may be removed, unground till put in, and the process continued.

If one part of a tile or slab grinds faster than another, the adjustment of that tile in the basket may be

changed, so that the whole edge shall be ground uniformly.

By the use of such a basket as described I perform the work more rapidly, better, and at less cost than by any of the devices heretofore in use.

What I claim as my invention, and desire to secure by Letters Patent, is—

1. A tile-grinding basket, consisting of a frame, *a*, two or more pressure-blocks, *d*, and to each a nut, *c*, on a screw, *e*, and with or without an interposed spring, *e*, the parts specified being so arranged as to hold the tile or slabs vertically while their edges are being ground, substantially as described.

2. The inclined rests *m*, adjustable as described, in combination with the frame *a*, bars *m*, and adjusting and holding-devices, for the purposes set forth.

In testimony whereof, I, the said PETER C. RENIERS, have hereunto set my hand.

PETER C. RENIERS.
